RUDDER GUARD

Henry W. Lange, Waretown, N.J.
(R.F.D. 1, 115 Bloomfield Road, Barnegat, N.J. 08005)

Filed June 13, 1972, Ser. No. 262,277

Term of patent 14 years

Int. Cl. D12—99

U.S. Cl. D71—1 Z

FIG. 1

FIG. 5

FIG. 4

FIG. 6

FIG. 3

FIG. 1 is a perspective view showing my rudder guard as applied to the lower region of an outboard motor, the latter being shown in phantom for illustrative purposes only.

FIG. 2 is a top plan view showing my rudder guard, the bottom plan view being identical but inverted.

FIG. 3 is a side view taken from the lower side of FIG. 2 in the drawing.

FIG. 4 is a rear view taken from the left of FIG. 2.

FIG. 5 is a side view taken from the top of FIG. 2.

FIG. 6 is a front view taken from the right of FIG. 2.

I claim:

The ornamental design for a rudder guard, as shown and described.
